UNITED STATES PATENT OFFICE

2,278,956

BUILDING CONSTRUCTION

Martin Wagner, Cambridge, Mass.

Application September 18, 1940, Serial No. 357,268

18 Claims.

(Cl. 20—2)

This invention relates to new and useful improvements in building construction, and relates more particularly to a novel building unit which may be divided into one or more rooms, or may be employed as a single room unit, and a plurality of such room units may be placed in side-by-side relationship and joined by intercommunicating passageways. In the event that more than two of such room units are desired, it is preferred to arrange the several units in such a fashion as to provide the passageways leading from a central unit.

In its broader aspect, the invention relates to a completely novel prefabricated building construction comprising a substantially hemispherical structure formed from a plurality of preformed panels, each being of similar construction and being shaped in the form of a spherical triangle, the panels being joined together along their meeting vertical edges by novel interlocking means. Each panel is desirably formed in upper and lower sections, the upper sections in all instances being identical in construction, and the lower sections including solid wall sections, sections with door and window openings, sections forming passageway openings, and other special sections containing closets, baths, etc. In relatively small building units a panel may be constructed in a single, unitary piece, whereas in relatively large units the panel structure may be formed in three or more sections, smaller rather than larger sections being preferred in order to facilitate handling and shipping.

A particular object of the invention is the provision of a floor-level building composed of single standardized room units of hemispherical shape which allow complete freedom in orientation in respect of sun, vista, prevailing winds, privacy, etc., these results being achieved by positioning the window and door openings in any part of the structure to suit the particular circumstances of the location, and likewise by placing the individual room units in any position to suit the individual demands of the user.

Another object of the present invention is the provision of an improved type of building unit which may be readily and quickly assembled as well as disassembled, and wherein the entire building structure composed of one or more of such room units may be increased or decreased at will.

A further object of the present invention is the provision of an improved building unit of the type described which is hemispherical in

shape, thus providing the least possible resistance to wind and gales, providing for the most rapid draining of water without the application of gutters, drain pipes, or the like, and for the warding off of snow loads. A structure of this type absorbs the maximum amount of heat from the sun during cold periods, and also provides means on the inside of the structure for gathering the dead air in the pinnacle of each room wherein it can be easily let off by means of a fan positioned adjacent to such pinnacle.

Yet a further object of the invention is the provision of an improved building structure comprising a plurality of such single-room units which provide easy escape from the structure in case of fire, and the spaced single-room units connected through passageways function like fire sluices or bulkheads.

Another object of the invention is the provision of a novel type of building construction wherein the entire structure may be quickly assembled and dismantled, and, if desired, shipped to another location. By employing housing of this type the owner thereof is not required to purchase the ground upon which the structure is to be placed but may merely rent the ground, and when the period of effective use in that location terminates he may dismantle the house, move it to another location by truck or other conveyance, and reassemble it. The interlocking panel construction is such that the structure suffers little or no depreciation as a result of dismantling and re-assembling.

A further important object of the invention is the provision of an improved type of building unit which is particularly adapted for temporary army housing, the room units being readily portable, and can be re-assembled in a minimum amount of time. In this connection the scattered plan pattern of single-room units in conjunction with the chosen construction provides for the utmost possible shelter from air raids by virtue of the fact that the hemispherical shape avoids sharp-edged shadows, and its shape lends itself to utilization of natural camouflage through overshadowing trees, overgrowing creepers or tendrils, or special coloring. The steel-clad construction of the panels further affords maximum protection from bursting shells and the like.

Yet another object of the invention is the provision of a rigid housing unit made of pre-formed interlocking panels of such rigid construction as to be substantially unaffected by hurricane, earthquake, dust storm, and other perilous elements. The wall and floor panels are constructed

to afford a maximum protection from heat in summer and cold in winter.

In the drawings:

Fig. 1 is a top plan view, partially in section, of the preferred embodiment of the present invention.

Fig. 2 is a rear elevation thereof, the view showing an elevation of the window panels.

Fig. 3 is a front elevation of the structure shown in Fig. 1.

Fig. 4 is a horizontal section taken on line 4—4 of Fig. 3.

Fig. 5 is a transverse vertical section taken on line 5—5 of Fig. 1.

Fig. 6 is a broken vertical section taken on line 6—6 of Fig. 1, the view showing one preferred means of securing the upper and lower sections of a wall panel together.

Fig. 7 is a broken section taken on line 7—7 of Fig. 1, the view showing one preferred means of securing the meeting vertical edges of the lower sections of two wall panels together.

Fig. 7A is a broken horizontal section similar to that shown in Fig. 7 but taken on a different plane, the view showing adjacent wall sections in abutting engagement.

Fig. 7B shows a modified form of panel-joining means, as well as a modified panel construction.

Fig. 8 is a broken vertical section taken on line 8—8 of Fig. 1, showing one preferred means of securing a wall panel to a floor section.

Figs. 9 and 10 are side and front elevations, respectively, of an upper section of a wall panel.

Figs. 11 and 12 are side and front elevations, respectively, of a lower section of a wall panel.

Fig. 13 is a broken horizontal section taken on line 13—13 of Fig. 2.

Fig. 14 is a broken section taken on line 14—14 of Fig. 13.

Fig. 15 is a vertical section through a lower section of a wall panel having a window opening, the section being taken on line 15—15 of Fig. 16.

Fig. 16 is a front elevation of the structure shown in Fig. 15.

Fig. 17 is a vertical section through a lower section of a wall panel having a door opening, the section being taken on line 17—17 of Fig. 18.

Fig. 18 is a front elevation of the structure shown in Fig. 17.

Fig. 19 is a plan view, partially in section, of a plurality of the individual housing units disposed about a central unit and in spaced relation thereto and to each other.

Fig. 20 is a vertical section taken on line 20—20 of Fig. 19.

Fig. 21 is a broken vertical section taken on line 21—21 of Fig. 19.

Fig. 22 is a broken section taken on line 22—22 of Fig. 19.

Fig. 23 is a broken horizontal section taken through a portion of the structure shown in Fig. 19.

Fig. 24 shows a plan view of a modified form of floor panel frame.

Fig. 25 is a section taken on line 25—25 of Fig. 24.

The preferred embodiment of a single housing unit 9 constituting the present invention is substantially hemispherical in shape, the apex of the hemisphere forming the uppermost point of the structure. The side walls are formed by joining together along their meeting vertical edges a plurality of panels, each shaped in the form of a spherical triangle. Each of these panels may, if desired, be formed in a single uni-

of insulating material placed in the openings. The innermost moisture barrier sheet 22 is then superimposed on frame section 28, and finally the inner facing of plywood 23 superimposed on frame section 28. The several sheets, together with the frame sections, may now be permanently secured together in any suitable manner.

One preferred means of accomplishing this is shown in Fig. 7 wherein a nut 30 is welded on the inner surface of sheet 19, and an elongated bolt 31, the head of which is in engagement with inner surface of plywood sheet 23, passes through the several frame sections, thus firmly securing the panel into a unitary, rigid structure. This fastening means is preferred since the outer metal sheet 19 is not pierced, thus avoiding the possibility of moisture penetrating into the panel and thus reducing the effectiveness of the insulating material.

The outer edges of the several strips 27, 28 and 29 forming the vertical portions of frame structure 26 lie on a single plane, which is at less than a right angle to the outer surface of panel 10, to form edges 15 and 16. The upper rail of the frame structure 26 is shown in Fig. 6, and the outer edges of strips 28 and 29 thereof lie on one plane, forming edge 34, whereas strip 27 projects thereabove forming a flange or projection 35.

At each upper corner of the panel, strip 29 is recessed at 36 and receives one corner of an apertured panel-joining plate 37, through which a plurality of screws 38 pass. In Fig. 8 a vertical section through the lower rail of frame 26 is shown, strips 28 and 29 being formed as in the other rails, the outer edges thereof lying on a single plane and forming edge 42. Outer strip 27 in this instance is somewhat wider, thus forming a downward projection or flange portion 43. It will also be noted that the lower edge of this panel section is covered by an extension of metal sheet 19 which extends around and covers such projecting portion 43, covering also the lower edge 42 of frame sections 28 and 29 and a portion of the inner surface of frame section 28.

Upper panel section 48, illustrated in Figs. 9 and 10, is similarly constructed with a plurality of spaced sheets and a substantially triangular frame structure 49 (Fig. 6) constructed like frame structure 26 and comprising strips 50 and 51, the latter having at each lower corner a recess 52 which receives one corner of plate 37, and an outer strip 53 of somewhat lesser width, and forming a recess 54 complementary to and which receives projection or flange 35 on panel structure 10. Vertical edges 55 and 56 are flat, and the upper edge 57 is likewise flat. If desired, the outer metal sheet may extend on its lower edge beyond the lower edge 54 of frame member 53, all as shown at 58 in Fig. 6, such portion overlapping the flange or projection 35 at the upper end of panel section 10.

In the frame structures shown in Fig. 7, the central or intermediate strip 29 is shown as projecting inwardly beyond the outer strips 27 and 28. It will be appreciated, of course, that strip 29 on its inner edge may lie on the same plane as the inner edges of strips 27 and 28. This particular type of frame structure is shown in Fig. 6 wherein the intermediate strip 51 of frame 49 along the lower edge of upper panel section 48 is flush with the inner edges of strips 50 and 53. Moreover, in Fig. 7 the panel section lying on the right of the panel-joining means shows the intermediate sheets 20 and 21 as extending out-

wardly to the very edge of the frame structure, whereas in the panel section to the left of the panel-joining means such intermediate sheets 20 and 21 terminate adjacent to the inner marginal edges of strips 27 and 28. These are merely two means of constructing the panels, and it will be appreciated that such panels may be varied in other ways without departing from the spirit of the invention.

10 In assembling the structure lower and upper panel sections 10 and 48 are first secured together in the manner shown in Fig. 6, the specific means for effecting the connection comprising the plate 37 and the screws 38. Two 15 panel structures comprising upper and lower panel sections 10 and 48 are now joined together in side by side relationship along their meeting vertical edges in the manner shown in Fig. 7. It was earlier pointed out that the respective vertical edges 15 and 16 of lower panel section 10, and the edges 55 and 56 of upper panel section 48, are flat and lie on a plane less than a right angle to the exterior surface of such panel sections, all as shown in Fig. 7A.

20 Along the vertical edges 15 and 16 of panel section 10, and 55 and 56 of panel section 48, there are formed a plurality of spaced, small semi-circular recesses 60, and accordingly when the meeting edges 16 and 15, respectively, of 25 two panel sections 10 are placed in meeting engagement there are formed a plurality of spaced apertures through which the securing means pass. One preferred form of such securing means between the meeting vertical edges of adjacent panels is illustrated in Fig. 7.

30 A plurality of internally threaded, metallic sleeves 61 are welded or otherwise secured at their outer terminals to an elongated metal batten 62 substantially semi-circular in transverse section and forming edges 62' which engage an elongated strip 64 of rubber or other similar weatherstrip material, the engagement between such edges 62' and the strip 64 being illustrated in Fig. 7A. At each point on the metal batten 62 wherein the metal sleeve 61 is secured the edges 62' of the batten are joined by a cross-piece 63 which may be welded or otherwise secured thereto, all as is shown in Fig. 7. Batten 62 extends the full length of the outer meeting vertical edges of the adjacent panels, and a screw 68 having a specially formed head 69 is received in the threaded metal sleeve 61.

35 At suitably spaced points along the inner surface of panel 10 there are formed a plurality of small, cut-out portions 65 through the inner plywood sheet 23 and the moisture barrier 22, thus exposing a small, semi-circular area of the inner surface of vertical rail 28 of the frame 26. The head 69 of screw 68 engages a washer 67 having a plurality of spaced prongs on its inner surface, and it will accordingly be apparent that as the screw 68 is moved in the threaded sleeve 61 a firm connection between the adjacent panels will be effected. The head 69 of screw 68 is further formed with a threaded aperture 71 40 which receives a screw 72, which secures an elongated wooden batten 73 that extends the full length of the panel.

45 A broken section through the floor and foundation structure is shown in Fig. 8. The floor structure comprises a plurality of sector-shaped floor sections 77. Each section includes a sector-shaped grating 78, and a broken plan view of several of such gratings is shown in Fig. 1. Upon the grating is mounted a moisture-repellent sheet

76. The floor section further comprises a lower laminated plywood sheet 79 and an upper laminated plywood sheet 81, between which insulating material 80 is positioned, the entire structure being formed around a frame, one rail 82 of which is illustrated in Fig. 8. On the upper surface of the floor section 77 a suitable composition flooring material 83 may be positioned. The outer terminals of the several floor sections rest upon cast iron footings 85, each footing having an upward projection 86 on the outer side thereof which supports an angle bracket 87 secured at its lower end to extension portion 86 by means of a screw 88.

The lower edge 42 of lower frame section 26 rests upon the upper surface of the horizontal portion of this angle bracket 87 and is secured to the upper vertical portion of such angle bracket by means of a bolt 89, such bolt passing into an internally threaded sleeve 91 welded or otherwise secured at its outer terminal to the inner surface of outer metal sheet 19. A baseboard 90 is then secured to the inner surface of the panel section 10 overlying the outer periphery of floor section 77.

It will be apparent from the foregoing that the several panel structures comprising upper and lower panel sections are firmly secured together along their meeting vertical edges at their lower ends by means of the several bolts 89 just described. Moreover, the adjoining panel structures are further firmly secured together by means of plates 37 joining the several corner sections of the upper and lower panel sections. Accordingly, the batten strips 62 which are in engagement with the resilient strip 61 covering the outer meeting vertical edges of the adjacent panel structures are not designed primarily to impart rigidity to the entire room unit.

In the event, however, that a greater measure of rigidity is desired along these meeting edges the structure illustrated in Fig. 7B may be employed. In this instance the outer metal sheet 19' of the panel section 10' is formed with an outwardly extending beading 92 which is substantially semi-circular in transverse section, and a strip of rubber or other resilient material 64' covering the adjoining beadings is engaged by means of a specially formed, elongated metal strip 93 having two spaced concave portions which engage the strip 64', which in turn engages the beading 92 along the vertical edge of each adjacent panel section 10'.

Between the two spaced concave portions of strip 93 there is formed a flat, intermediate elongated area 93' having a plurality of spaced apertures through which a conventional headed bolt 64 may pass, such bolt residing in the complementary recesses 60' formed at spaced points along the vertical edges of the panel 10'. At its inner end the bolt passes through a washer 67' and its terminal is received within a nut 69'. The screw 72' in this instance, which secures the elongated wooden batten strip 73', is also received in the threaded aperture of the nut 69'. In other words, the head of the bolt is located on the exterior of the structure rather than on the interior, and the bolt is of such length as to cause its inner terminal to project only half-way or thereabouts into the nut 69'.

The panel section 10' in this instance is shown in a slightly modified form wherein the intermediate moisture barrier sheet 21 is eliminated entirely, and accordingly frame sections 28 and 29 are replaced by a single frame section 28', and 75

frame section 27' is the same as frame section 27 in the preferred embodiment. In this panel section an air space 95 is provided between outer metal sheet 19' and heat-reflecting sheet 20', and suitable insulating material 44' is positioned between heat-reflecting sheet 20' and inner moisture barrier 22'. The inner surface of the panel section is faced with a plywood sheet 23' as in the preferred embodiment.

10. In the single housing unit each structure comprises a plurality of the panel structures of the type just described, each panel structure preferably being formed in upper and lower sections 48 and 10, respectively, as previously described. The upper panel sections 48 are of the same construction in each instance, and special lower panel sections are formed for window and door openings, and for other purposes.

A preferred form of panel 100 having a window opening is shown in Figs. 15 and 16, and a preferred form of lower panel section 101 having a door opening is shown in Figs. 17 and 18. Panel 100 comprises vertical side portions 102 and 103, a curved lower section 106 terminating at its lower end in a lower edge 104, and an upper section 107 terminating at its upper end in an edge 105. The upper terminal 109 of curved portion 106 forms a lower seat for a window frame 110, and the lower edge 111 of portion 107 forms the upper support for such window frame.

Side portions 102 and 103 are desirably formed of two sheets of laminated plywood 117 and 118, shown in detail in Fig. 13, and having a plurality of spaced recesses 119 therebetween through each of which a flat metal bar 120 passes. The two plywood sheets 117 and 118 are desirably held in meeting engagement by means of a plurality of spaced bolts 121. The several strips 120 are longitudinally movable in the several recesses 119, and at the outer end of each strip 120 a hooked portion 122 is formed, such hooked portion passing through an aperture 123 in an elongated metal batten 124 similar to batten 62, and having a plurality of spaced cross-pieces 125 within which the apertures 123 are formed, and in the portions of the batten between such cross-pieces the edges of the batten engage a weatherstrip 126 similar to weatherstrip 64.

It will be noted from Fig. 13 that inner plywood strip 118 is of lesser width than strip 117, thus forming a recess 128 to receive the marginal edge of panel section 10. When panel 100 is to be secured in place the vertical edge 15 of panel 10 is positioned as shown in Fig. 13, weatherstrip 126 and batten 124 properly positioned, and metal strips 120 drawn inwardly in the following manner.

At its inner end strip 120 is secured to an internally threaded sleeve 128. A screw 129 engaging a washer 134 is received within the sleeve and the head 130 of such screw rotated until strip 120 has been drawn inwardly to a point wherein batten 124 is in firm engagement with weatherstrip member 126. Screw head 130 likewise has a threaded aperture 131 therein, and a wooden batten 132 is secured to the inner vertical edge of member 103 by means of screw 133 passing into such head. Sections 106 and 107 of panel structure 100 are formed of the same laminated construction as panel 10 in any of its several forms, and the details of such construction will not be again set forth.

The outer surfaces 135 of such portions 106 and 107 are of sheet steel, indicated at 135, and likewise the outer surfaces of portions 102 and

103 are covered with sheet steel, indicated at 136 in Fig. 13. The window panel section 100, shown in Figs. 15 and 16, constitutes the preferred embodiment of such structure. It will be appreciated, however, that a panel section having a window opening may be formed by simply forming an opening of appropriate size in lower panel section 10 and placing the usual window frame therein.

Panel section 101, illustrated in Figs. 17 and 18 and having the door opening therein, constitutes a panel portion 142 which may be constructed in substantially the same manner as panel section 10 with an appropriate opening 143 therein. A substantially triangular panel portion 144 having a vertical edge 145 and a curved edge 146 is employed on each side of the opening, the edge 146 being suitably secured to one edge of opening 143 in panel section 142. The two triangular panel portions 144 are desirably secured together at their upper ends by means of an angular strip 147, and adjacent to the forward ends of such panel portions a vertical panel 148 is secured, such panel having an opening 149 therein which receives a door frame 150.

A substantially similar panel structure 154 is shown in Figs. 1 and 3 to form an externally disposed closet or shower-bath compartment. In this instance the panel portion 155 is constructed similar to panel portion 142 of panel structure 101, and the triangular portions 156 are provided with curved extension portions 157 forming the roof and side walls of the compartment. The outer edge of the compartment is closed by means of a panel portion 158 preferably having a window 159 therein.

Upper panel sections 48 are of such size as to leave a small circular opening 163 therein, which opening receives a closure plate 164 which may contain an air-conditioning unit or other ventilating device adapted to draw stale air from the interior of the structure.

A plan view of several interconnected individual room units is shown in Fig. 19, each of the room units being designated by the reference numeral 9, the central unit, however, being designated as 9'. One preferred form of interconnecting means comprises a panel structure 154 identical with structure 154 in Fig. 3, in each room unit, the outer ends of the triangular side walls 156 being connected by means of curved, substantially rectangular side wall panels 168 joined together at their upper ends, as shown at 169. If desired, each panel structure 154 may be provided adjacent to its outer end with a vertical panel 170 having an opening 171 therein, all as shown in Fig. 20.

In Fig. 21 a broken section showing the joinder of two floor sections 77, together with a vertical wall 168 is shown. The floor sections 77 terminate in vertical portions 175 through which a bolt 176 passes, such bolt likewise passing through a lower vertical portion 177 of an angle bracket having a horizontal portion 178 and another vertical portion 179. The lower end of member 168 is formed with horizontal members 180 which are joined to vertical portion 179 of angle bracket 177 by means of a bolt 182 which is secured within an internally threaded sleeve 183, welded or otherwise secured to a metal sheeting 184 surrounding the lower end of member 168.

The details of the means for securing vertical wall portion 158 at its lower end to a floor section 77 is shown in Fig. 22. In this instance the vertical wall portion 158 is formed at its lower

end with a flange 188 covered by a metal sheet 189, and an angle bracket 190 is secured to the cast iron footing 85 by means of a bolt 191. A bolt 192, passing through the upper portion of angle bracket 190, is received within an internally threaded sleeve 193 welded at one end thereof to the inner surface of metal sheet 189.

Fig. 23 shows an alternative means of securing a closet section 154 to a lower panel section 10. In this instance, wall 195 is secured to frame member 196 in any suitable manner, and a plurality of bolts 197 pass into metal sleeves 198 which in turn are welded to a batten 199 in substantially the same manner as is shown in Fig. 7.

The preferred embodiment of the triangular floor unit 77 was shown to include a metal grating 78. A modified form of support 210 for the floor section is shown in Fig. 24, the frame being formed from a plurality of metal bars 211 which are substantially T-shaped in transverse section comprising a horizontal portion 212 and a vertical portion 213. The structure is formed in the manner shown in Fig. 24, the terminals of the several bars 211 being suitably welded together. In this instance the bars are mounted on cylindrical footings 214, there being formed a vertical recess 215 in the vertical portion 213 of each bar.

It will be appreciated that the foregoing described structures are capable of many changes and modifications without departing from the spirit of the invention thereof as defined by the appended claims. In other words, such embodiments, though presently preferred, are nevertheless illustrative only and may be changed or modified in any manner known to those skilled in the art, such embodiments being by way of illustration only and are not to be taken in any limiting sense.

What I claim is:

1. A substantially hemispherical building structure formed from a plurality of pre-formed panels shaped substantially in the form of a spherical triangle and being secured together along their vertical edges, each panel comprising a frame and a plurality of superimposed wall forming sheets, of substantially the same size as the frame, carried thereby.

2. A substantially hemispherical building structure formed from a plurality of pre-formed panels shaped substantially in the form of a spherical triangle and being secured together along their vertical edges, each panel comprising a frame structure comprising a plurality of superimposed frame sections and a plurality of spaced wall forming sheets carried thereby.

3. A substantially hemispherical building structure formed from a plurality of pre-formed panel structures comprising upper and lower panel sections, which, when joined together, form a substantially spherical triangle having a convexly curved outer surface, such panel structures being secured together along their meeting vertical edges, each panel section comprising a frame structure and a plurality of spaced wall forming sheets carried thereby.

4. A substantially hemispherical building structure formed from a plurality of pre-formed panels shaped substantially in the form of a spherical triangle and means for securing said panels together along their vertical edges, each panel comprising a frame and a plurality of spaced wall forming sheets carried thereby, said panel securing means comprising a batten strip covering the inner and outer meeting vertical edges

of the panels and a plurality of spaced fastening means passing between such meeting edges and securing said strips in place.

5. A substantially hemispherical building structure formed from a plurality of pre-formed panels shaped substantially in the form of a spherical triangle and being secured together along their vertical edges, each panel comprising a frame structure comprising a plurality of superimposed frame sections and a plurality of spaced wall forming sheets carried thereby, heat and cold insulating material interposed between at least two of said wall forming sheets, and a circular floor structure comprising a plurality of sector-shaped floor sections joined together and supporting the lower edges of the panels around the peripheral marginal edge of said floor structure.

6. A building structure comprising a plurality of curved panel structures, each of said structures being formed in substantially the shape of an elongated spherical triangle and being joined together along their vertical edges to form a substantially hemispherical building unit, the apexes of the several panel structures forming the apex of the unit and the edges opposite such apexes forming the base of the curved wall sections, each panel structure comprising upper and lower panel sections, each section comprising a frame and a plurality of spaced wall forming sheets carried by said frame and extending substantially to the edge thereof, and a floor structure comprising a plurality of sector-shaped floor sections joined together to form a circular floor, the peripheral edges thereof receiving and supporting the bases of the panel structures.

7. A building structure comprising a plurality of panel structures, each being convexly curved on their outer surfaces and being formed in substantially the shape of an elongated spherical triangle, the several panel structures being joined together along their vertical edges to form a substantially hemispherical unit, the apexes of the several panel structures forming the apex of the unit and the edges opposite such apexes forming the base of the wall sections, each panel structure comprising a frame and a plurality of spaced wall forming sheets carried by said frame, and a circular floor structure, the peripheral edges thereof receiving and supporting the bases of the wall sections.

8. A building structure comprising a plurality of curved panel structures, each formed in substantially the shape of an elongated spherical triangle joined together along their vertical edges to form a substantially hemispherical unit, and a circular floor section supporting said unit, each panel structure comprising upper and lower panel sections, each comprising a frame and a plurality of spaced wall forming sheets carried by said frame and extending substantially to the edge thereof, the outermost sheets being formed of metal, the intermediate sheets being formed from heat-reflecting and moisture-resistant materials, respectively, and the innermost sheet being of fibrous material.

9. A building structure comprising a plurality of curved panel structures, each formed in substantially the shape of an elongated spherical triangle joined together along their vertical edges to form a substantially hemispherical unit, and a circular floor section supporting such unit, each panel structure comprising upper and lower panel sections, each comprising a frame and a plurality of spaced wall forming sheets carried by said

frame and extending substantially to the edge thereof, at least one of said lower panel sections having a door opening therein and another having a window opening therein.

5. 10. A building structure comprising a plurality of curved panel structures, each formed in substantially the shape of an elongated spherical triangle joined together along their vertical edges to form a substantially hemispherical unit, each 10 panel structure comprising upper and lower panel sections, each comprising a frame and a plurality of spaced wall forming sheets carried by said frame and extending substantially to the edge thereof, and a floor structure comprising a plurality of sector-shaped floor sections joined together to form a circular floor, the meeting corner portions of the upper and lower panel sections having a recess therein and an apertured plate being received at each corner thereof in one recess and being secured therein, and means 15 for securing the lower marginal edges of each panel structure to the adjacent marginal edge of its circular floor.

25 11. A building panel provided with a convexly curved outer surface and being shaped generally in the form of a spherical triangle, which, when a plurality of such panels are joined together along their meeting vertical edges, form a substantially hemispherical building structure, said 30 panel comprising a frame defining the outer edges of the structure, and a plurality of wall forming sheets carried by said frame, the frame and the sheets constituting a load-carrying element.

35 12. A building panel provided with a convexly curved outer surface and being shaped generally in the form of a spherical triangle, which, when a plurality of such panels are joined together along their meeting vertical edges, form a substantially hemispherical building structure, said 40 panel comprising a frame defining the outer edges of the structure, and a plurality of spaced wall forming sheets carried by said frame and extending substantially to the edges thereof, the outermost sheet being formed of sheet metal and the innermost sheet of laminated wood, a heat-reflecting sheet and a moisture-resistant sheet interposed therebetween, and a sheet of heat and cold insulating material interposed between at least two of said wall forming sheets.

45 13. A building panel provided with a convexly curved outer surface and being shaped generally in the form of a spherical triangle, which, when a plurality of such panels are joined together along their meeting vertical edges, form a substantially hemispherical building structure, said panel comprising upper and lower panel sections, each section including a frame defining the outer edges of the structure, and a plurality of spaced wall forming sheets carried by said frame and extending substantially to the edges thereof, the outermost sheet being formed of sheet metal and the innermost sheet of wood, a heat-reflecting sheet and a moisture-resistant sheet interposed therebetween, the corner sections of the meeting edges of the upper and lower panel sections having a recess therein, and a plate received in said recesses and adapted to rigidly secure the panel sections, and adjacent panels, together.

50 14. A pre-fabricated building structure comprising a plurality of spaced, substantially hemispherical room units positioned in spaced relation, one to the other, each unit formed from a plurality of curved, substantially triangular wall panels joined together along their meeting verti-

cal edges, at least one panel in each room unit being formed with an opening therein, and an interconnecting passageway joining such openings in two adjacent structures.

15. A pre-fabricated building structure comprising a central room unit and a plurality of room units disposed radially therefrom, and an interconnecting passageway between the central unit and the other units, each room unit being substantially hemispherical in shape and being formed from a plurality of curved, substantially triangular pre-formed panels joined together along their meeting vertical edges, at least one panel in each unit having a window opening therein and one panel in the central unit having a door opening therein.

16. A building structure comprising a plurality of spaced, substantially hemispherical room units and connecting passageways between such units, each unit being formed from a plurality of curved, substantially triangular rigid panels, each panel comprising a plurality of sheets of wall forming material and a frame structure supporting such sheets, a substantially ground level, circular floor structure supporting each room unit and comprising a plurality of sector-shaped sections, each formed with a supporting frame and plurality of layers of floor forming sheets mounted thereon.

17. A prefabricated building comprising a plurality of panel sections curved convexly on their

outer surface and being shaped generally in the form of an elongated spherical triangle, and joined together along their longitudinal edges to form a substantially hemi-spherical structure.

18. A building structure comprising a circular base supporting the structure, each panel section including upper and lower interlocking panel members, each member comprising a frame and a plurality of wall forming sheets supported along their marginal edges by the frame, insulating material positioned between at least two of said sheets and at least two of said sheets having an air space therebetween, the sheets and the frame forming a load-bearing structure.

19. A building structure comprising a plurality of curved panel sections shaped generally in the form of an elongated spherical triangle and joined along their meeting edges to form a substantially hemi-spherical structure, each section including upper and lower interlocking members, each of such members comprising a load-bearing frame structure and a plurality of spaced wall forming sheets, the outermost sheets being formed of metal, another sheet being formed from heat-reflecting material and a third sheet being formed from moisture-resisting material, at least one of the lower panel members having a window opening therein and another having a door opening.

MARTIN WAGNER.
